G. E. CHENOWETH.

Harvester Rake.

No. 19,749.

Patented March 30, 1858.

UNITED STATES PATENT OFFICE.

GEO. E. CHENOWETH, OF BALTIMORE, MARYLAND.

IMPROVEMENT IN HARVESTERS.

Specification forming part of Letters Patent No. 19,749, dated March 30, 1858.

To all whom it may concern:

Be it known that I, GEORGE E. CHENOWETH, of the city of Baltimore, in the State of Maryland, have invented an Improvement in Reaping-Machines; and I do hereby declare the following to be a correct description of the same, reference being had to the annexed drawing, which is a perspective view of the machine complete.

My invention consists in compensating wear in the worm of the driving cylinder or drum by making the cylinder of adjustable parts, all as hereinafter more particularly set forth.

In the drawing, letters G G represent a spur-wheel and pinion, the wheel being attached to the inside of the large driving-wheel of the machine and the pinion fastened to the end of the axis of the grooved cylinder. This simple gearing drives the drum or cylinder D D, which has a groove or worm, C C, arranged as shown, which, by means of the rolling or friction pin P, works the horizontal sliding bar B B, which is in line with and connected to the knife-bar K K.

The drum D D is formed of two cylinders, sliding freely on a feathered axis, as shown, and adjusted and fixed in any desired position by means of nuts N N on the axis. The parts of the drum may be approximated by means

of these nuts whenever the wear of the worm requires to be compensated. The pin P has a friction-roller upon it to facilitate its play in the groove C C.

The operation is as follows: As the drum D D revolves, driven by the spur-gearing G G, it communicates a reciprocating motion to the pin P and the slide-bar B B, attached to it. This bar, being attached to the knife-bar K K, imparts a corresponding motion to the knives.

The advantages of this machine are simplicity of construction, directness of action, compensation for wear, and the absence of that uncertainty of stroke which has been so important an objection to cam-machines.

Having thus described my invention, what I claim is—

Compensating for the wear of the worm or groove in the driving-cylinder by making the parts of that cylinder adjustable, as described, thus giving increased certainty to the action of the cutters.

The above specification signed and witnessed this 4th day of March, A. D. 1858.

GEO. E. CHENOWETH.
